United States Patent Office

Des. 218,098
Patented July 21, 1970

218,098

SPELLING TEACHING MACHINE

Ronald D. Halliburton, Miami, Fla., assignor to Allied Leisure Industries, Inc., Hialeah, Fla., a corporation of Florida

Filed June 6, 1969, Ser. No. 17,557

Term of patent 14 years

Int. Cl. D19—08

U.S. Cl. D25—1

The figure is a front perspective view of a spelling teaching machine showing my new design.

The sides not shown are the same as the plain sides shown.

I claim:

The ornamental design for a spelling teaching machine, as shown and described.
